UNITED STATES PATENT OFFICE.

CHARLES L. REIZENSTEIN, OF PITTSBURGH, PENNSYLVANIA.

DESIGN FOR A GLASS PLATE OR SIMILAR ARTICLE.

52,171.

Specification for Design.

Patented July 9, 1918.

Application filed July 16, 1917. Serial No. 180,947. Term of patent 14 years.

To all whom it may concern:

Be it known that I, CHARLES L. REIZENSTEIN, a citizen of the United States, and residing at 310 South Rebecca St., city of Pittsburgh, county of Allegheny, and State of Pennsylvania, have invented a new, original, and ornamental Design for a Glass Plate or Similar Article, of which the following is a specification, reference being had to the accompanying drawing, forming a part thereof.

Figure 1 is a plan view of a glass plate showing my new design; Fig. 2 is a fragmentary sectional view on the line 2—2, Fig. 1, of a part of the plate showing a design.

The back or underside of the rim of the

plate, as shown, has a background coat of color applied thereto. The face of the rim of the plate has a color line ornamentation on either side of said background area, and to the face of the rim of the plate also is applied the design in flowers and foliage, as shown, which is in relief and gives the natural colors of the flowers and foliage.

I claim:

The ornamental design for a glass plate or similar article, as shown and described.

CHARLES L. REIZENSTEIN.

Witnesses:

J. R. KELLER,
JOHN F. WILL.
